Patented Jan. 2, 1917.

FIG. 1.

FIG. 2.

FIG. 3.

UNITED STATES PATENT OFFICE.

MAX H. NEWMAN, OF ATLANTIC CITY, NEW JERSEY.

VEHICLE-SIGNAL.

1,211,215.

Specification of Letters Patent. Patented Jan. 2, 1917.

Application filed May 17, 1916. Serial No. 98,074.

To all whom it may concern:

Be it known that I, MAX H. NEWMAN, a citizen of the United States, and a resident of Atlantic City, in the county of Atlantic and State of New Jersey, have invented a new and Improved Vehicle-Signal, of which the following is a full, clear, and exact description.

The invention relates to vehicle signals such as shown and described in the application for Letters Patent of the United States, No. 67267, filed by me on December 16, 1915.

The object of the invention is to provide a new and improved vehicle signal, which is very simple in construction and arranged to enable the driver of the vehicle to throw a pertinent sign into position in case the driver intends to stop or turn out to the right or to the left, thus giving a signal to a following vehicle of the intentions of the driver.

In order to accomplish the desired result, use is made of stop and turn-out signs mounted to swing on the same pivot and normally disposed in an inactive position, actuating levers connected with the said sign for swinging any one of the same from normal inactive position into display position, controlling levers under the control of the driver of the vehicle, flexible connections connecting the said controlling levers with the said actuating levers, a return lever having a means extending in the path of the said actuating levers, and manually controlled means connected with the said return lever to return a displayed sign and its actuating mechanism to normal inactive position.

A practical embodiment of the invention is represented in the accompanying drawings forming a part of this specification, in which similar characters of reference indicate corresponding parts in all the views.

Figure 1 is a cross section of a vehicle body provided with the improved vehicle signal; Fig. 2 is an enlarged sectional elevation of the vehicle signal on the line 2—2 of Fig. 3; Fig. 3 is a sectional plan view of the same on the line 3—3 of Fig. 2; and Fig. 4 is an enlarged sectional plan view of the casing and the controlling levers mounted therein.

The vehicle signal is mounted on a casing 10 provided at one side with a tube 11 fastened by a suitable bracket 12 to one side

arm 13 of the wind shield, as plainly indicated in Fig. 1. In the upper portion of the casing 10 is arranged a pivot 14 on which are mounted to swing, up and down, signs or semaphores 15, 16 and 17, of which the sign 15 bears the legend "Left," the sign 16 bears the legend "Stop," and the sign 17 bears the legend "Right" (not shown). Normally the signs 15, 16 and 17 hang in a vertical inactive position within the casing 10, but each one of the signs can be swung outward and upward into horizontal position to display the corresponding legend to a following vehicle. Thus, as shown in Figs. 1 and 2, the sign 16 is displayed thereby indicating to a following vehicle that the driver intends to stop the vehicle he is driving.

The signs 15, 16 and 17 are actuated by actuating levers 20, 21 and 22 mounted to swing independently one of the other on a pivot 23 held on the casing 10. Each of the levers 20, 21 and 22 is provided with a pin 24 engaging a slot 25 formed in the corresponding sign 15, 16 or 17, adjacent the fulcrum thereof, so that when a lever is actuated the corresponding sign 15, 16 or 17 is swung into display position and held therein until the actuating lever is returned, as hereinafter more fully explained. The lower ends of the levers 20, 21 and 22 are connected with wires 30, 31 and 32 which extend through the tube 11 and through a tube 33 connected by a coupling 34 with the tube 11, the tube 33 opening into a casing 35 attached to the dashboard or other part of the vehicle within close proximity of the driver in charge of the vehicle. The wires 30, 31 and 32 are connected with controlling levers 40, 41 and 42 fulcrumed in the casing 35 and extending through slots 36 formed in the bottom of the casing 35 so as to be within convenient reach of the driver. The controlling levers bear legends corresponding to the legends on the signs 15, 16 and 17 actuated by the levers 20, 21 and 22 with which the corresponding levers 40, 41 and 42 are connected by the wires 30, 31 and 32. Normally the outer ends of the levers 40, 41 and 42 extend to the right and when it is desired to swing any one of the signs 15, 16 and 17 into display position it is only necessary for the driver to take hold of the outer end of the corresponding lever 40, 41 or 42 and swing the same from

105 110

the right to the left so that a pull is exerted on the corresponding wire 30, 31 and 32 whereby a swinging motion is given to the corresponding lever 20, 21 or 22 to swing 5 the desired sign 15, 16 or 17 into display position. By reference to Fig. 2, it will be noticed that the slots 25 are curved to hold the sign in display position as long as the corresponding lever has been actuated, as 10 above explained. The stop lever 41 is preferably located at the middle of the casing 35 and is flanked by the levers 40 and 42 so that the driver can readily take hold of the proper lever for moving the desired sign 15 into display position.

In order to return the displayed sign and its actuating lever, the corresponding wire and the corresponding controlling lever to normal inactive position, the following arrangement is made: The actuating levers 20, 21 and 22 are provided with upwardly extending arms 50, 51 and 52 normally in alignment with each other and engaged near their free ends by a pin 53 held on the upper end of a lever 54 fulcrumed at its lower end at 55 on the casing 10. The lever 54 is connected with one end of a wire 56 extending through the tubes 11 and 33 into the casing 35 to connect with a return lever 57 fulcrumed in the casing 35 and extending through a slot 37 arranged in the top of the said casing. When a sign is moved into display position then the corresponding actuating lever 20, 21 or 22 imparts a swinging motion to the lever 54 by its arm 50, 51, or 52 in engagement with the pin 53. This swinging movement from the right to the left given to the lever 54 causes the wire 56 to swing the return lever 57 into the position shown in Fig. 2, and when it is desired to return the sign to inactive position the operator takes hold of the outer end of the lever 57 and swings the same from the right to the left whereby a pull is exerted on the wire 56 and a return swinging movement is given to the lever 54, so that the pin 53, engaging the arm 50, 51 or 52, the corresponding actuating lever 20, 21 or 22, returns the latter to normal inactive position 50 and with it the corresponding sign 15, 16, or 17. From the foregoing it will be seen that the return lever 57 is actuated whenever one of the levers 40, 41 or 42 is moved from the right to the left, and this lever is returned 55 to normal position on the operator next imparting a return swinging movement to the lever 57.

The device shown and described is very simple and durable in construction and is 60 composed of comparatively few parts, not liable easily to get out of order.

The back of the casing 10 is preferably provided with a mirror 60 so as to enable the

driver to obtain a view of the road in the rear of the vehicle. 65

Having thus described my invention, I claim as new and desire to secure by Letters Patent:

1. In a vehicle signal, the combination of stop and turn-out signs, manually controlled actuating levers each connected with a corresponding sign to swing the latter from normal inactive position into display position, and a manually controlled return lever having a pin extending into the paths of the 70 said actuating levers to be actuated by either one of said actuating levers on swinging a sign into display position and to return a displayed sign and its actuating lever to normal inactive position. 80

2. In a vehicle signal, the combination of stop and turn-out signs, manually controlled actuating levers each connected with a corresponding sign to swing the latter from normal inactive position into display position, each of the said actuating levers having an arm, and a manually controlled return lever having a pin engaged by the said arms of the actuating levers to be actuated by either one of the said arms on swinging a corresponding sign into display position the said return lever serving to return a displayed sign and its actuating lever to normal inactive position. 85

3. In a vehicle signal, the combination of stop and turn-out signs mounted to swing and normally disposed in an inactive position, actuating levers connected with the said signs for swinging the same from normal inactive position into display position, 90 controlling levers under the control of the driver of the vehicle, flexible connections connecting the said controlling levers with the said actuating levers, a return lever having a pin extending in the paths of the said actuating levers, and manually controlled means connected with the said return lever to return a displayed sign and its actuating mechanism to normal inactive position. 95

4. In a vehicle signal, the combination of stop and turn-out signs mounted to swing and normally disposed in an inactive position, actuating levers connected with the said signs for swinging the same from normal inactive position into display position, 100 controlling levers under the control of the driver of the vehicle, flexible connections connecting the said controlling levers with the said actuating levers, a return lever having a pin extending in the paths of the said actuating levers, a flexible connection connected at one end with the said return lever, and a manually controlled lever connected with the other end of said flexible connection. 115
